BRASSIÈRE

Jules Brandt, Brooklyn, N. Y.

Application March 2, 1955, Serial No. 34,836

Term of patent 14 years

(Cl. D20—4)

To all whom it may concern:

Be it known that I, Jules Brandt, a citizen of the United States, residing at Brooklyn, in the county of Kings and State of New York, have invented a new, original, and ornamental Design for a Brassière, of which the following is a specification, reference being had to the accompanying drawing, forming part thereof.

In the drawing:

Fig. 1 is a front perspective view of a brassière showing my new design;

I claim:

The ornamental design for a brassière, substantially as shown.
